UNITED STATES PATENT OFFICE.

GEORGE RADFORD, OF OAKLAND BEACH, RHODE ISLAND, ASSIGNOR TO RICHMOND
LACE WORKS, OF ALTON, RHODE ISLAND, A CORPORATION OF MAINE.

DESIGN FOR LACE.

Application filed July 19, 1922. Serial No. 3,127. Term of patent 3½ years.

To all whom it may concern:

Be it known that I, GEORGE RADFORD, a subject of George V, King of England, residing at Oakland Beach, in the county of Kent and State of Rhode Island, have invented a new, original, and ornamental Design for Lace, of which the following is a specification, reference being had to the accompanying drawing, forming part thereof.

The figure is a face view of the lace, showing my new design.

I claim:

The ornamental design for lace, as shown.
GEORGE RADFORD.
